UNITED STATES PATENT OFFICE

THOMAS L. TALIAFERRO, OF CHICAGO, ILLINOIS, ASSIGNOR TO PHOENIX-HERMETIC COMPANY, OF CHICAGO, ILLINOIS, A CORPORATION OF ILLINOIS

METAL JAR CLOSURE

Application filed January 8, 1927. Serial No. 159,895.

The invention relates to new and useful improvements in metal caps or jar closures, and more particularly to a cap or jar closure having a thread or threads formed therein adapted to engage a cooperating thread or threads on the jar for securing the cap or closure to the jar.

An object of the invention is to provide a cap or closure of the above type wherein the lower edge portion of the cap or closure is slightly enlarged, inturned and curved so as to form a smooth rounded bead at the outer face of the closure, the outer surface of which bead is a continuation of the outer surface of the depending flange in which the thread or threads are formed.

In the drawings which show by way of illustration one embodiment of the invention—

20 Figure 1 is a view partly in side elevation and partly in section, showing on an enlarged scale, my improved cap or closure and a section of a jar with which it is adapted to be used;

25 Fig. 2 is a section through a portion of the cap or closure on even a more enlarged scale, and

30 Fig. 3 is a view similar to Fig. 1, but showing the cap or closure and the jar as provided with a plurality of threads instead of a single thread.

The invention is directed to a metal cap or closure for jars. One of the purposes of the invention is to provide a metal closure wherein the outer face of the depending flange or skirt of the closure shall have exposed to view only the outer surface of the metal from the top of the closure to the extreme lower edge of the depending portion.

40 The cap or closure is preferably made of one piece of metal. The metal may be lacquered or decorated in the sheet in the usual manner.

45 It is then cut and drawn to form a proper blank which is subjected to the proper tools for knurling the depending flange or skirt of the cap, and forming the thread or threads in said depending portion. The invention is especially directed to the construction of the lower edge of the cap. The lower edge of the blank is bent outwardly, thence down-

wardly and thence inwardly so as to form a smooth rounded bead at the outer face of the cap or closure at the lower edge of the depending flange or skirt. The extreme lower edge is inturned so that the hand of a person screwing the cap or closure on or off from the jar is protected from contact with the raw edge of metal. The raw edge of the metal is also concealed from view by this inturning of the extreme lower edge.

55 Referring more in detail to the drawings, my improved cap or closure consists of a single piece of metal shaped so as to form a top portion 1 and a depending flange or skirt 2. Adjacent the top portion, the flange is provided with a knurl 3 of the usual character.

60 At the extreme lower edge of the flange, the metal is bent outwardly at 4, thence downwardly at 5, and thence inwardly at 6. This forms a curved bead of substantially uniform cross section throughout, and extending all the way around the lower edge of the cap or closure. As shown in Figures 1 and 2, the flange or skirt is provided with a single

65 thread 7 which extends a little more than once around the closure. This thread is formed in the usual way, and includes inwardly curved portions and outwardly curved portions which are adapted to engage

70 the outwardly projecting thread 8 on the jar 9. The thread begins at a point just below the knurl, and terminates at a point just above the bead. In Fig. 3 of the drawings, I have shown a plurality of threads 10, 10, and

75 the jar is likewise provided with a plurality of threads 11 with which the multiple threads on the cap or closure cooperate. The invention is not directed to the particular construction or arrangement of the threads, except

80 that the threads are to be located between this bead at the lower edge of the closure and the knurl adjacent the top of the closure. The portion at the extreme lower edge of the flange is formed to be inturned at 6, which 85 conceals the raw edge of the metal from view, and aids in the forming of the curved bead at the lower edge of the flange. The portion 4 at the lower edge of the flange is formed to be bent outwardly. This is for the purpose of 90 providing the entrance opening to the cap,

so that the thread on the jar can pass through said entrance and engage the thread groove or thread projection in the flange or skirt of the cap. In other words, the interior diameter of the extreme lower edge of the flange is slightly greater than the maximum diameter of the jar mouth at the thread thereon.

In my improved form of cap or closure, the same surface of the metal is exposed to view throughout the entire extent of the flange as at the top of the closure, and if the closure is, therefore, decorated in a certain color by the enameling or coloring thereof, this color will be uniform throughout the entire extent of the cap or closure as viewed when on the jar. Furthermore, the exterior of the flange of the cap or closure is free from pockets, so that little or no dust will accumulate on the side wall of the cap. This bead at the lower edge of the cap or closure strengthens the edge and forms a cap wherein the lower edge thereof is symmetrical all the way around the cap.

The subject-matter described above is fully disclosed in a prior application Serial No. 25 475,922, filed by me on June 8, 1921.

It is obvious that minor changes may be made in the shaping of the parts without departing from the spirit of the invention as set forth in the appended claim.

Having thus described the invention, what I claim as new and desire to secure by Letters-Patent, is—

A metal closure for jars comprising a top and a depending flange formed integral therewith, said flange having a thread formed therein adapted to engage a thread on the jar, the upper portion of said depending flange being knurled and the lower portion of the depending flange being curved outwardly and downwardly, thence inwardly to form a strengthening bead, the outer surface of said depending flange being continuous and extending in a downward direction, the extreme inner diameter of said inturned edge portion being greater than the diameter of the threads on the jar, said threads in the depending flange being disposed between the knurled portion and said bead, said bead being of substantially uniform cross section throughout.

In testimony whereof, I affix my signature.
THOMAS L. TALIAFERRO.
